UNITED STATES PATENT OFFICE.

WELLINGTON B. WHEELER, OF EL SEGUNDO, CALIFORNIA.

DESIGN FOR A BILL-BOARD ARCH.

56,044.

Specification for Design.

Patented Aug. 10, 1920.

Application filed May 11, 1920. Serial No. 380,669. Term of patent 3½ years.

To all whom it may concern:

Be it known that I, WELLINGTON B. WHEELER, a citizen of the United States, residing at El Segundo, in the county of Los Angeles and State of California, have invented a new, original, and ornamental Design for Bill-Board Arches, of which the following is a specification, reference being

had to the accompanying drawing, forming a part thereof.

The figure is a perspective of a bill board arch showing my new design.

I claim:

The ornamental design for a bill board arch as shown.

WELLINGTON B. WHEELER.
